[57] CLAIM

The ornamental design for a support for a fishing rod, as shown and described.

DESCRIPTION

FIG. 1 is a front elevational view of a support for a fishing rod, showing my new design;

FIG. 2 is a rear elevational view thereof;

FIG. 3 is a right side elevational view, the left side being a mirror image thereof;

FIG. 4 is a top plan view thereof;

FIG. 5 is a bottom plan view thereof;

FIG. 6 is a perspective view thereof;

FIG. 7 is a front elevational view of a second embodiment;

FIG. 8 is a rear elevational view thereof;

FIG. 9 is a right side elevational view, the left side being a mirror image thereof;

FIG. 10 is a top plan view thereof;

FIG. 11 is a bottom plan view thereof;

FIG. 12 is a perspective view thereof;

FIG. 13 is a front elevational view of a third embodiment;

FIG. 14 is a rear elevational view thereof;

FIG. 15 is a right side elevational view, the left side being a mirror image thereof;

FIG. 16 is a top plan view thereof;

FIG. 17 is a bottom plan view thereof; and,

FIG. 18 is a perspective view thereof.
